UNITED STATES PATENT OFFICE

WILLIAM G. POWELL, OF ALTOONA, PENNSYLVANIA

DIE FOR MAKING JOURNAL-BOX WEDGES

Application filed October 28, 1927. Serial No. 229,470.

This invention relates to railway car journal box wedges, and has for its primary object a novel method of manufacturing drop forged wedges such that the same will readily fit into place in the journal box without the usual grinding and finishing processes now universally resorted to after the wedge leaves the forging press.

Another object of this invention is to provide a new and practical method of manufacturing drop forged wedges whereby the sides of the wedge which engage the journal box are surfaces made parallel with each other as well as parallel with the side of the journal box, thus eliminating the usual draft universally found in journal box wedges made in drop forged dies of the usual design and manufacture.

A further object of this invention is, to provide a practical means of manufacturing journal box wedges, such that the cost of manufacture will be reduced, and all wedges so manufactured will be duplicates of each other, and will readily fit into place in the journal box without alteration after leaving the die.

With the above and other objects in view, which will be more readily apparent as the nature of the invention is better understood, the same consists in the novel construction, combination and arrangement of parts hereinafter more fully pointed out, illustrated and claimed.

It will be quite readily understood by those skilled in the art to which this invention belongs that the same is susceptible to some minor structural changes and modifications, but a preferred and practical embodiment of the present invention is shown in the accompanying drawings, in which—

Figure 1 is a vertical sectional view of a pair of die members showing the end elevation of the wedge therein.

Figure 2 is a longitudinal sectional view taken at right angles to Figure 1; the line of section being at the left-hand edge of the wedge shown in position in the forming dies in Fig. 1.

Figure 3 is a transverse sectional view of a

standard design of journal box, showing my improved wedge in position therein.

Figure 4 is a longitudinal sectional view of a standard journal box, showing my improved journal box wedge in position and also shows its relation to the journal box bearing.

Similar reference numerals designate corresponding parts throughout the several figures of the drawings.

Railway car trucks are provided with outside journals, designated by the numeral 10. The journal consists of a longitudinal cylindrical portion on which a bearing 11 is positioned. Between the top 12 of the journal bearing and the journal box 13 a journal box wedge 14 is positioned, and the primary object of the journal box wedge 14 is, to keep the journal bearing 11 in its proper position on the top of the journal 10, as shown in Figures 3 and 4 of the drawings.

The journal box wedge is provided with dependent flanges 15, the outside surfaces 16 at either side of which are made parallel with each other, and conform in vertical alignment with corresponding sides 17 of the journal box. In order to provide for the inaccuracies of the present method of drop forging the wedge, as well as some slight lateral movement between the wedge and the journal box, the surface 16, that is designed to impinge against the surface 17, is made to extend to approximately one-third of the longitudinal length of the wedge, as shown in Fig. 2 of the drawings.

In drop forging the journal box wedge, using the present accepted method, it is necessary, in order to remove the wedge from the die, to give the face 16 a taper or draft, which must be removed by a grinding process or otherwise machining the faces such that the two sides are parallel, and my present invention eliminates this process as well as insures that all wedges are duplicates of each other as no finishing is required after leaving the die.

Accordingly, with a view of properly forming the journal box side engaging surfaces of the wedge, designated by the numeral 16, at either side thereof, it is proposed to provide upper and lower die members 18 and 19, each

having the necessary recesses made therein for forming the wedge from the metal placed between the same, while the surfaces 16 at either side of the wedge will be parallel with each other and perpendicular to the top surface 20 of the wedge.

To this end it is proposed to form the complementary die recesses of the dies 18 and 19 in such a way that the transverse axis of the complete recess is inclined with respect to the line of division between the dies, and, likewise, the longitudinal axis of the complete die recess is also disposed at an angle to the line or plane of division on which the die members 18 and 19 separate.

The transverse inclination of the complete die recess is illustrated in Figure 1 of the drawings, and the longitudinal inclination is illustrated in Figure 2 of the drawings.

By referring to Figure 1, it will be observed that the side 16 of the wedge is formed entirely in the upper die 18, while the opposite face 16^a is formed in the lower die 19, and this method of assembling the dies makes it possible to form the above faces 16 and 16^a parallel to each other and perpendicular to the top face 20, which is formed entirely in the bottom member 19 of the die.

By this arrangement of the upper and lower dies, all of the various angular faces throughout the wedge are formed such that when the die members are separated the wedge may be readily removed without draft or taper on either face 16 or 16^a, but the proper draft obtained at all other places where such are required.

Having thus described my invention, what I claim and wish to be secured by Letters Patent is—

In the art of forging journal box wedges, a pair of cooperating die members provided with complementary recesses together providing a chamber conforming in contour to the contour of the wedge, said die members being adapted for straight line movement towards and from one another and having their meeting surfaces disposed in planes at right angles to the direction of their movement towards and from one another, said chamber being disposed with both its transverse and longitudinal axes at an inclination with respect to the plane of the meeting faces of said die members whereby the sides and the ends of the wedge may be formed with parallel surfaces, respectively, and whereby the wedge may readily be disengaged from the recess in each die member.

In testimony whereof I affix my signature.
WILLIAM G. POWELL.
